UNITED STATES PATENT OFFICE.

EWALD KOERNER, OF DRESDEN, GERMANY, ASSIGNOR TO UNITED CIGARETTE MACHINE CO. INC., OF LYNCHBURG, VIRGINIA, A CORPORATION OF VIRGINIA.

CIGARETTE MACHINE.

Application filed December 7, 1927, Serial No. 238,261, and in Japan April 26, 1926.

The object of the present invention is to provide means for guiding the belts of cigarette machines in such manner that the belt is relieved of strains which are inevitable under belt handling devices now employed.

The invention will be described with reference to the accompanying drawing in which—

10 Figure 1 illustrates, in longitudinal sectional elevation, belt guiding means constructed in accordance with the invention;

Figure 2 is a plan view of the embodiment illustrated in Figure 1, and partly in 15 section;

Figure 3 is a transverse section on the line 3—3, Figure 2;

Figures 4, 5 and 6 are respectively transverse sections on the lines 4—4, 5—5 and 20 6—6, Figure 1;

Figure 7 is a sectional elevation through the base of a discharge chute for tobacco and through the belt trough, and

Figure 8 is a perspective view of a belt 25 trough constructed in accordance with the invention.

In cigarette machines it is common to form a tobacco rod by means of suitable rolls acting upon tobacco which is fed upon 30 a moving tape running in a guide groove. Since the tape or belt must be endless, it is necessary to spread it out flat as it comes out of the U-formed groove. This flattening of the belt causes some severe difficulties 35 for there is the danger of folding and causing a great strain on the single strands of the belt. In order to overcome these difficulties it has been proposed to have the band slide over a tapered surface, but the end of 40 the tapered convex curved surface must be supplied with rollers or the like which on their part have the disadvantage that the belt is greatly strained in the middle, consequently tears occur which influence the even running, and forming of folds and 45 also cause great wear on the belts. Also it is difficult, when conical or curved guide plates are used, to control the further movement of the tobacco rod. The body used 50 for this purpose is very hard to make on account of its peculiar shape and also is very apt to damage the belt, the present invention will avoid this difficulty in that it eliminates guiding plates and insures the 55 natural out-flow of the belt, i. e. such an

opening up of the belt in that each phase of the belt over its entire width at any given moment has a given tension and also during the further motion of the belt an equal amount of tension is maintained. 60

In order to carry out the invention the belt comes off on to a cylindrical roller. This roller, in order to have an equal tension over the whole width of the belt, is so mounted that the top surface lies higher 65 than the bottom of the groove in which the belt is guided. Furthermore, guides are provided in order to prevent any folding over of the belt towards the inside of the groove which might be caused by certain irregularities in the belt itself. These 70 guides hold the band towards the outside in its natural path and on their inner sides have surfaces suitably shaped for the further transfer of the tobacco rod. 75

The tobacco passes from chute A onto a belt, indicated at 1, Figure 1, which is guided by the walls of a guide channel 2, illustrated more particularly in Figures 7 and 8. The guide channel lying immediately under the chute A has customarily been of wood or the like in which the groove was cut. It appears now that the best results are obtained when the cross section of the channel for its full length is an exact 80 half circle with ends vertically tangent and that is one object of this invention. In order to produce an accurately made channel member of this kind more easily, this invention provides that the channel member 85 be no longer made from a solid piece of material but formed from sheet metal which can be drawn or rolled into an accurate taper in a simple manner. The sheet metal channel member 2 can then be screwed to a support 3. The cross section of the metal channel member 2 is formed to a half circle along its entire length which is continued straight up in two parallel tangents. The semi-circular part forms in its axial direction an accurate half of a hollow cone. The sheet metal can best be formed in this manner; an accurate tapered rod is made by turning or grinding and around this the sheet of suitable material is drawn or rolled. 100 The outer ends of the piece are bent out to form flanges and fastened to support 3 by screws. 105

The belt passes from the receiving guide channel to a belt channel member 4, above 110

which rotates the usual forming roller 5, which has a semi-circular groove around its circumference. The formed tobacco rod 6 is carried along further and onto the strip 5 of paper 7 which is led over roller 8. The so-called forming belt 9 led over roller 10 receives the paper strip with the rod and carries the two along to completion by the forming and pasting devices customarily employed in cigarette machines and which are not shown, inasmuch as they form no part of the present invention.

The forming belt 1 is led over a belt receiving roller 12, the top of which lies, as shown in Figure 1, higher than the bottom of the channel in member 4, for a purpose hereinafter explained.

As the belt leaves the belt channel member 4 it enters a spreader comprising a wedge-shaped member 13 having spaced parallel inner walls equivalent to the thickness of the rod, and serving to guide the same. Wedge-shaped spreader 13 gradually spreads the belt toward normal position, the action being illustrated progressively by Figures 3 to 6 respectively. Wedge-shaped spreader 13 is carried by guide pieces 14, 14^x attached to side plates 15 which are secured to channel member 4 by means of screws 17, 17^x. In order that the members 15 may be swung upwardly, the receiving holes in members 15 for the screws 17^x may be slots, as indicated at 16, Figure 1. The wedge-shaped spreader 13 holds the belt during its passage from member 4 against bending inward, a bending which happens particularly with belts which have run a long time. As the rod leaves the wedge-shaped spreader 13 it passes upon roller 12 over which belt 1 is led.

The amount that the upper part of roller 12 is elevated above the bottom of the channel is regulated according to the breadth, the thickness, and material of the belt. As this can only be determined through experiment, it is therefore desirable to mount the roller adjustably in a vertical direction, although this is not absolutely necessary, since on cigarette machines of a certain kind the belts are made always the same width and thickness and of the same material.

The amount of the elevation is shown in Figure 1 by the dotted line and arrows 18.

The cigarette rod passes from roller 12 to a bridge 19. The guiding sides of the bridge can be made in two simple strips 55 partly cut at one end so as to extend practically to a point meeting a vertical line extending through the axis of the roller 12, the strip lying above the roller as shown in Figure 1, wherein only one strip is illustrated, the horizontal connecting member 19^x for the strips being shown in section. The bridge is a usual element in rod feeds and does not require detailed description.

The drawing shows the invention in combination with the so-called cigarette rod, but it can however naturally be used in combination with machines of other kinds, for example shell filling machines or the like or in any cigarette machine in which a rod 70 or otherwise round body is formed by means of a continuously running belt having a U-form and which passes from the U-form into the flat form.

Having described my invention what I 75 claim and desire to secure by Letters Patent is as follows:—

1. In cigarette machines, spreading means for a rod-carrying belt employed in connection with a belt guiding member with a U- 80 shaped cross section, comprising a roller upon which the belt is received, the periphery of the roller lying higher than the bottom of the channel in the belt guiding member, and a wedge-shaped member intermediate the guide member and the roller for engaging the upper surface of the belt.

2. In cigarette machines, spreading means for the rod carrying belt constructed in accordance with claim 1, and the wedge-shaped member comprising two separate sections, each section having an inner wall parallel with the inner wall of the other section and an oblique outer wall, said outer walls being rounded toward their lowermost 95 surfaces and means for suspending said wedge member.

In testimony whereof, I have signed my name to this specification.

EWALD KOERNER.
